LAUNDRY MACHINE

James B. Kirby, West Richfield, Ohio, assignor,
by mesne assignments, to The Apex Electrical
Manufacturing Company, Cleveland, Ohio, a
corporation of Ohio, as trustee

Application March 10, 1927, Serial No. 174,208

3 Claims. (Cl. 210—63)

This invention relates to laundry machines and has for its objects the provision of an improved construction and mounting of extracting device; the provision of an extractor of increased rigid-

ity and stability and decreased vibration; the provision of new and improved expedients for supporting such an extractor and accommodating its vibration; the provision of a new and improved type of extractor unit adapted for use with other 10 and independent laundry equipment; while further objects together with a clearer definition of those objects above named will appear as the description proceeds.

In the drawing accompanying and forming a 15 part of this application I have illustrated certain simple, physical embodiments of my inventive idea although it will be understood that the drawing is intended to be merely illustrative of the principles of my invention, and not limiting upon 20 me as regards proportions, constructions, or modes of application.

Fig. 1 is a top plan view of a series of set-tubs having one of my improved extractors applied thereto; Fig. 2 is a central sectional view corresponding substantially to the line 2—2 of Fig. 1; Figs. 3 and 4 are side elevations showing alternative constructions of the centrifuge element; Fig. 5 is a detail sectional view corresponding to the line 5—5 of Fig. 3; and Fig. 6 illustrates a modified type of support.

My improved laundry machine as herein constructed comprises a rigid member 1 carrying an upright journal bearing 2 and a sheet metal casting 3 having a drain pipe 4. Journaled in the bearing 2 is a shaft 5 operatively connected by any suitable driving mechanism with an electric motor 6 carried by the member 1. For the purpose of convenience I have here illustrated a friction drive, but any known mechanical movement 35 can be employed. The upper end of the shaft is squared or fluted as shown at 7 for the reception of the centrifuge container. This container is preferably made with a circular bottom member formed with a central elevated hollow boss 10, and a peripheral upright wall 11 spaced radially therefrom, the two defining an annular upwardly-facing trough 12. The top of the boss terminates in a cap 13 which is recessed for the tight reception of the upper end of the shaft 5, and the boss 40 is hollow beneath so that the bearing rises a substantial distance into the container. Secured to the outer wall 11 is the sheet metal side wall 14 of the container which is characterized by being largest at the bottom and becoming narrower 45 with increasing height, its top being surmounted

and stiffened by a suitable rim element 15 securely affixed thereto and defining a central circular opening 16 for the reception of the articles to be centrifuged.

This container is formed with water discharge 50 openings 18 at its point of greatest diameter (and elsewhere also if desired as indicated at 19 in Fig. 4) and these apertures may be formed either in the wall 11 as shown in Fig. 2 or may be confined to the sheet metal part 14 as illustrated in 55 Fig. 3 or may be formed in both places. However, it is preferred to omit the apertures 19, and form only such apertures adjacent to the point of largest diameter as are necessary for the discharge 60 of the liquid at that point, inasmuch as any 70 unnecessary perforations increase the liability of injury to the fabrics by engagement with the edges thereof. Furthermore the formation of the side walls of the container of downwardly flaring 75 shape facilitates the use of imperforate sheet 76 metal since the downward slant of the walls causes the acceleration of gravity to be added to the centrifugal force tending to extract the water 80 from the fabrics inside the container. It is also possible, and in some cases desirable, to form the 85 side walls of vertically corrugated sheet metal as shown in Figs. 3 and 5, thus facilitating the discharge of the water by providing channels for its flow. In this case the water discharge openings 18 should be formed at the bottoms of the channels (looking from within), and the same need be 90 only of very narrow dimensions, which reduces the likelihood of the clothes becoming caught 95 therein, while affording adequate egress for the liquid.

For supporting this machine I preferably provide a frame 20 having hooks 21 to engage the lip of a laundry tub, such as the set-tubs illustrated in Figs. 1 and 2, combined with a bracing part 22 adapted to engage the outer wall of such tubs and hold the frame rigidly. Preferably two 100 hooks 21—21 are provided, spaced apart so as to straddle a tub partition if desired, as shown in Fig. 1, and also to facilitate the ready application 105 of the device to the side of a circular wash tub if desired. The frame is also provided with a horizontal portion 23 to which the member 1 is attached by means of a flexibly yielding element 24 such as a rubber cushion which shall permit a limited gyrator movement of the bearing and 110 centrifuge so as to compensate in substantial degree for an unbalanced arrangement of the articles therein. It is within my invention to substitute floor legs 25 for the bracket 20 as shown in Fig. 6.

Inasmuch as the casing 3 is rigid with the bearing 2, said casing will gyrate along with the bearing and container, but being made light and of small inertia, such gyration exhibits no injurious effect. Furthermore the heavy parts, such as the motor and driving mechanism, are located close to the cushion so that the leverage exerted thereby is at a minimum. The upwardly tapering shape of the container further acts to reduce the gyrating tendency, partly by compelling a more central insertion of the articles, and partly by holding the articles nearer the axis of rotation at that part of the container which is furthest from the bearing, namely at the top. It will be apparent upon consideration that the injurious effect of any unbalance weight will be less at the bottom of the container where the leverage upon the bearing is small than at the top of the container where the leverage is comparatively great. The upwardly tapering shape also produces a more rigid container structure for a given weight of metal, facilitates the extraction of the liquid, and tends to pack the articles closer to the bottom of the container as the liquid is extracted.

It will be understood that many changes in shape, detail and construction can be made within the scope of my invention, and that certain of the different ideas herein disclosed can be used

30

80

independently of other of said ideas, wherefore I do not limit myself except as specifically set forth in my several claims which are intended to be construed each independently of limitations contained in other claims.

Having thus described my invention what I claim is:

1. A casing for a centrifuge having an upright bearing rigidly secured in its bottom, a supporting frame, and a flexible-cushioning element connecting said frame and casing adjacent to said bearing. 85

2. The combination with a bearing, of a frame, a flexible element connecting said frame and bearing and adapted to permit limited gyratory movement of said bearing, a motor rigid with said bearing, a centrifuge journaled to said bearing, a casing rigid with said bearing and surrounding said centrifuge, driving connections between said motor and centrifuge, and means for securing said frame detachably to a laundry tub. 90

3. In a laundry machine, an extractor, a casing therefor, a driving device, and a supporting frame, said extractor, casing, and driving device constituting a unit, means flexibly securing such unit to said frame, and means for securing said frame to a laundry tub. 95
